UNITED STATES PATENT OFFICE.

FREDERIC P. LYMAN, OF KANSAS CITY, MISSOURI.

BED-TABLE.

1,179,536.

Specification of Letters Patent. Patented Apr. 18, 1916.

Application filed June 25, 1914. Serial No. 848,309.

To all whom it may concern:

Be it known that I, FREDERIC P. LYMAN, a citizen of the United States, residing at Kansas City, in the county of Jackson and

5 State of Missouri, have invented certain new and useful Improvements in Bed-Tables, of which the following is a specification.

This invention relates to bed tables, and has for its object to produce a table for the 10 convenient use of a person sitting up in bed, my special object being to produce a table having legs capable of adjustment to substantially level the table regardless of the level of the support for the table legs.

15 A further object is to produce a bed table of simple, strong, durable, inexpensive and attractive appearance.

With these objects in view, the invention consists in certain novel and peculiar features of construction and organization as 20 hereinafter described and claimed; and in order that it may be fully understood, reference is to be had to the accompanying drawing, in which:—

25 Figure 1, is an end view, partly in section, of a table embodying my invention. Fig. 2, is a side view of the table, the dotted lines indicating how the legs are folded to inoperative position. Fig. 3, is an inverted plan 30 view of the table.

In the said drawing, 1 is the table top of oblong rectangular form and 2 are parallel cross bracing strips, secured to the table top near each end thereof.

35 3 are cross pieces upon which the table top is adapted to rest in use, and said cross pieces are hinged at 4 to the table top and are adapted when upright to bear against the bracing strips 2. The cross pieces are preferably rounded at their lower edges and formed in such edges at opposite sides of the central longitudinal plane of the table are downwardly diverging sockets 5, and outward of said sockets are similar but more 45 widely diverging sockets 6.

7 are supporting legs, provided with reduced portions or tenons 8 at their upper ends, adapted to engage the sockets 5 or 6, accordingly, as it is desired to increase or 50 diminish the height of the table, and when it is desired to dispose the table top at an incline with respect to the plane of the lower ends of the legs, the legs at one side of the longitudinal center of the table may be 55 shifted or adjusted for engagement with a different set of the sockets, that is to say, if

the tenons of all of the legs are engaging sockets 5, two of the legs will be adjusted to dispose the tenons thereof in the adjacent sockets 6.

60

In Fig. 1, dotted lines indicate the adjustment referred to, it being understood that the right hand legs 7 rest upon the most depressed portion of a bed, for instance, that portion which is most depressed because it 65 sustains the greater part of the weight of the body when one is sitting up in bed, the dotted line indicating that portion of the bed adjacent the knees, and which, under ordinary conditions, will not be depressed to the 70 same extent as the other portion referred to, because less weight is imposed upon it.

9 is a block secured to the underside of the table top at the center thereof and fastened to said block is a resilient locking strip 10, 75 the same engaging recesses 11 in the cross pieces 3 when the latter are vertical or unfolded, to hold them in such position, and when the legs are folded to inoperative position, as indicated by dotted lines, Fig. 2, the 80 strip 10 will fit against the outer faces of cross pieces 3 and therefore hold the legs in folded position for convenience in storing the table or in carrying it from one place to another.

85

12 is a perforated plate to form an ink well holder, and said plate is pivoted at 13 so that it may be turned at right angles to the position shown in Fig. 3 and therefore project outward beyond the adjacent edge 90 of the table top so that an ink well may be supported in the perforation without danger of being turned over accidentally.

90

14 is a plate secured to the underside of the table at one end and hinged thereto is 95 a hasp 15 adapted when not in use to fit over a screw eye 16 secured in the underside of the table top. When the screw eye is turned at right angles to the position shown, the hasp can be swung downward from engagement with said screw eye and then be utilized for hanging the table upon a wall or other support.

100

This table is adapted for use only upon a bed or cot, and when in use the table top 105 will be arranged transversely across and just in front of the user, and to level the table as hereinbefore referred to, the legs thereof nearest the body of the user will occupy the sockets 5, and the other legs will 110 be caused to engage the sockets 6 at the opposite side of the longitudinal center of the

table. By this arrangement of the legs the plane of the table and the bottoms of the legs converge toward the foot of the bed, but as the support for the legs occupying 5 the sockets 6 is higher than the support for the other pair of legs, the table top will occupy a substantially horizontal position and hence may be used by the occupant of the bed with the greatest ease and convenience.

From the above description it will be apparent that I have produced a table for use upon a bed or cot which embodies the features of advantage enumerated as desirable and which may be modified in minor particulars without departing from the principle of construction involved or sacrificing any of the advantages of the appended claims and in this connection I desire to state that when the table is used as 15 a writing table it is desirable to incline it toward the user by setting the table legs nearest the body of the user in sockets 6 so as to effect a decided lowering of the edge 20 of the table nearest to the user as by thus 25

inclining the table a letter or other matter may be written with greater convenience than if the table is substantially level, as will be readily understood.

I claim:

A table comprising a top, cross pieces secured to the top at the underside of the same and each provided with a pair of upwardly converging sockets at each corner of the table, the sockets at each corner converging upward with respect to the other sockets in the same cross piece, and a leg to support each corner of the table, the legs of the same cross pieces engaging either of the sockets at the same corner accordingly as 30 it is desired to dispose them at equal or unequal angles and therefore hold the table top parallel or tilted with respect to the plane of the lower ends of the legs.

In testimony whereof, I affix my signature, in the presence of two witnesses.

FREDERIC P. LYMAN.
